UNITED STATES PATENT OFFICE.

WILLIAM ANSELM COATES, OF CHORLTON-CUM-HARDY, AND GEORGE EDWARD GITTINS AND DAVID REGINALD DAVIES, OF STRETFORD, MANCHESTER, ENGLAND, ASSIGNORS TO WESTINGHOUSE ELECTRIC AND MANUFACTURING COMPANY, A CORPORATION OF PENNSYLVANIA.

CIRCUIT BREAKER.

Application filed June 5, 1922. Serial No. 566,032.

Our invention relates to electric switches and particularly to means for supporting the fixed contact members of such switches and conducting the current thereto.

A very usual construction of oil-immersed switches comprises two fixed contact members connected by means of a movable bridge piece, the fixed contact members being supported on two parallel rods or studs 10 mounted on and depending from the cover or top casting of the switch, through which rods or studs the current is conducted to said contact members. In the case of switches which are employed to carry very 15 heavy currents, the magnetic repulsive force between the two rods or studs may be so large, when the current is flowing, as to cause a displacement of the contact members at the ends of said rods, particularly 20 where the rods are of a considerable length, and this displacement may interfere with the correct operation of the switch.

Our invention has for its objects the provision of means for preventing the distortion of a pair of parallel conductors under magnetic stresses and the provision of an improved form of switch apparatus.

According to the present invention, the conductors supporting the fixed contact 30 members are made concentric, one of the conductors being tubular and enclosing within it the other conductor in the form of a rod, suitable insulation being provided between the two conductors. The fixed contact members may be mounted on the ends 35 of the rod and tube, respectively, in any suitable manner, and are positioned for engagement by the movable bridging member of the switch.

40 The single figure of the drawing is a view, partially in section and partially in side elevation, of a switch embodying our invention.

The switch shown comprises an oil tank 45 1 and a switch head or casting 2 of usual construction, two stationary contact members 3 and 4 and two movable bridging members 5 which, as shown, are preferably of the brush type comprising a bundle of 50 laminated conducting strips 6 clamped between supporting members 7 and 8, by screws 9, the said bridging members 5 being moved by means of a switch-operating

rod 10 through mechanism which will be hereinafter described in detail.

The stationary contact members 3 and 4, are, respectively, connected with and supported by a tubular conductor 11 and a rod conductor 12 concentrically disposed within the tubular conductor 11. The contact 60 members 3 and 4 may be connected to the conductors 11 and 12 by any well known means, such as by screw threaded engagement, as illustrated. The inner rod conductor 12 is insulated from the tubular conductor 11 by means of a tube 13 of insulating material which is preferably continued beyond the ends of the tubular conductor 11 to the lower contact member 4 at one end and to a terminal block 14 clamped to the 70 upper end of the rod 12. A tube 15 of insulating material covers the tubular conductor 11 and extends between the contact member 3 and a terminal member 16 clamped to the upper end of the conductor 75 11. The concentric insulated conductors 11 and 12 pass through a perforation 17 in the switch head 2 and are supported on the latter by means of a flanged bush member 18.

The stationary contact members 3 and 4 may be of equal lateral width but, preferably, the upper contact member 3 is of greater width than the lower contact member 4, the contact faces of both contacts being at a small angle to the axis of the conductors 11 and 12 instead of parallel therewith. With this arrangement, the bridging members 5, when closed, will occupy positions slightly inclined from the vertical as 80 shown. The bridges act symmetrically on either side of the contact members 3 and 4, whereby a symmetrical distribution of the stresses is set up when the switch is closed with the requisite force and the conductors 85 11 and 12 thereby relieved from any undue strain.

Supporting brackets 8, for the brushes 6 are pivotally mounted upon members 19 which are themselves pivoted below the lower contact member 4, upon an extension 20 of the latter. Each of the members 19 comprises two parallel plates that embrace the supporting members 8 and the projection 20. Rotative movement of the members 19 about 105 their pivotal connection upon the projec-

tion 20 in an upward direction, to bring the brush members 6 simultaneously into engagement with the fixed contact members 3 and 4, is effected by means of a bell-crank 5 lever 20a which is pivotally connected at a point intermediate its ends to the tail portion 21 of one of the members 19. One arm of the lever 20a is pivotally connected to the switch-operating rod 10 which, as will be 10 well understood, may be moved in a substantially vertical direction by hand operation or by electrical or power means. The other arm of the lever 20a is pivotally connected in the axial line of the switch conductors 11 and 12 to a link 22 which is of a 15 length substantially equal to that of the shorter arm of the lever 20a and is pivotally supported upon the tail portion 21 of one of the members 19, the link 22 and the arm 20 of the lever 20a connected to it constituting a form of toggle joint. Normally, when the switch is opened, the members 19 fall so that their upper ends rotate outwardly and the brushes occupy the position shown in 25 dotted lines. The tail portions 21 of the members 19 approach one another and the switch operating rod 10 falls to the position indicated in dotted lines so that the point of connection between the link 22 and the lever 20a is raised. Positive separation 30 of the bridging members 5 from the stationary contact members 3 and 4 may be obtained by mechanically depressing the operating rod 10 which causes the link 22 and lever 20a to turn the members 19 about the extension 20, thereby moving the bridging members 5 to their dotted line positions.

Circuit breaker apparatus embodying certain features of the above described operating mechanism is disclosed in our co-pending application, Serial No. 566,031, filed June 5, 1922 (Case No. 9925).

It will be understood that, in addition to the main breaks provided between the contact members 3 and 4 and the bridges 5, shunt or arcing contacts may also be provided of any suitable type.

With the concentric arrangement of the conductors 11 and 12, it will be readily seen 50 that deformation of the conductors by reason of the magnetic field set up by heavy current passing through the switch cannot occur except at the bridge portions 6 of the switch, while the switch operating mechanism may be sufficiently powerful to prevent any appreciable tendency to movement of the bridges away from the contact members 3 and 4.

Various changes in detail and arrangement may be made without departing from the spirit and scope of the invention, as defined in the accompanying claims.

We claim as our invention:

1. In a circuit breaker, two electrical conductors disposed in concentric relation and

having insulation interposed therebetween, the inner conductor having its extremity extending beyond the adjacent end of the outer conductor, and a contact member on each of the said ends arranged concentrically thereof, the peripheral sides of the respective contact members being in parallelism and a bridging member for connecting the contact members. 70

2. In a circuit breaker, two electrical conductors disposed in concentric relation, the ends of the inner conductor extending beyond the outer conductor and provided with contact members and a movable bridging member for connecting the contact members. 75

3. In a circuit breaker, two electrical conductors disposed in concentric relation, the ends of the inner conductor extending beyond the outer conductor, two adjacent ends of the conductors being provided with terminal members and the other two ends thereof being provided with switch contact devices and a bridging member for connecting the switch contact devices. 85

4. In an electric switch, the combination 90 with a pair of concentrically arranged conductors provided with longitudinally spaced terminal members, of oppositely disposed bridging members movable laterally with respect to the said conductors and means for effecting a simultaneous engagement between said bridging members and said terminals. 95

5. In an electric switch, the combination 100 with a pair of concentrically arranged conductors each provided with a terminal member longitudinally spaced with respect to the other terminal member, of a bridging member for completing a circuit across the said terminals and means for moving the bridging member into and out of engagement with the said terminals. 105

6. In an electric switch, the combination 110 with a pair of concentrically arranged conductor members each provided with a terminal member lying in longitudinally spaced relation to the other terminal member, the outer terminal being of smaller width than the other terminal, a bridging member pivotally supported at a point beyond the outer terminal, and means for rotatively moving the bridging member into engagement with the said terminals. 115

7. In an electric switch comprising two 120 fixed contact members, one disposed vertically above the other, a pair of cooperating bridging members symmetrically arranged on either side of said contact members and pivotally carried upon upwardly projecting arms of a pair of bell-crank levers which are pivoted at a common point beneath the lower fixed contact member, the other arms of said bell-crank levers being connected together by a toggle link, and means for operating the said bell-crank levers. 125

8. An electric switch comprising two concentric conductors, a fixed contact member mounted upon the outer of the two conductors, a fixed contact member mounted upon the inner of the two conductors and disposed vertically beneath the previously mentioned contact member and spaced therefrom, and a substantially vertically disposed bridging member cooperating with said fixed contact

members and mounted for movement in a **10** substantially horizontal direction.

In testimony whereof, we have hereunto subscribed our names this 18th day of May, 1922.
